UNITED STATES PATENT OFFICE.

SAMUEL F. RICHARDSON, OF EAST JORDAN, MICHIGAN.

POTATO-KNIFE AND HOLDER.

1,177,804.

Specification of Letters Patent.

Patented Apr. 4, 1916.

Application filed December 2, 1915. Serial No. 64,734.

To all whom it may concern:

Be it known that I, SAMUEL F. RICHARDSON, a citizen of the United States, residing at East Jordan, in the county of Charlevoix 5 and State of Michigan, have invented a new and useful Potato-Knife and Holder, of which the following is a specification.

The device forming the subject matter of this application is adapted to be employed 10 for cutting up potatoes to be used as seed.

The invention aims to provide a structure of this kind which may be positioned in an accessible manner with respect to the operator.

15 Another object of the invention is to provide novel means whereby the knife holding table may be disposed at various angles.

A further object of the invention is to 20 provide novel means whereby the angle between the knife and the surface of the table may be changed.

25 A further object of the invention is to provide, in a device of the type described, a combined means whereby the knife is held at different angles with respect to the table, and whereby the table may be held at different angles with respect to the horizontal.

It is within the province of the disclosure 30 to improve generally and to enhance the utility of devices of that type to which the present invention appertains.

With the above and other objects in view which will appear as the description proceeds, the invention resides in the combination 35 and arrangement of parts and in the details of construction hereinafter described and claimed, it being understood that changes in the precise embodiment of the invention herein disclosed can be made 40 within the scope of what is claimed without departing from the spirit of the invention.

In the accompanying drawing:—Figure 1 shows the invention in side elevation; Fig. 2 is an end elevation; Fig. 3 is a section 45 taken approximately on the line 3—3 of Fig. 1; Fig. 4 is a top plan of the foot plate.

In carrying out the present invention there is provided a base 1 which may be a box, a bench or other object upon which the 50 operator may sit, the operator ordinarily straddling the base 1.

The invention comprises a support embodying a foot plate 2 provided with openings 3 adapted to receive securing elements 55 (not shown) whereby the foot plate 2 may be assembled with the base 1 near to one end

of the base. The foot plate 2 carries an up-standing lug 4 enlarged at its forward end as shown at 5 to form inclined shoulders 6.

The invention includes a standard which 60 preferably but not necessarily comprises spaced strips 7, the lower ends of which bear against opposite faces of the lug 4. A combined clamping and pivot element preferably in the form of a bolt and nut structure 8 passes through the lower ends of the strips 7 and through the lug 4.

The invention comprises a table composed 65 preferably of a pair of angle members 9, embodying horizontal, oppositely projecting flanges 11 and vertical, depending flanges 10.

The ends of the strips 7 which go to 70 make up the standard, lie against the outer faces of the vertical flanges 10, and through the upper ends of the strips 7 which go to

75 make up the standard and through the vertical flanges 10 of the angle members 9 passes a combined clamping and pivot element, preferably in the form of a bolt 12. The bolt 12 passes through the lower end of a blade 80

14, the lower end of the blade being located between the vertical flanges 10 of the angle members 9. The blade 14 preferably is sharpened as shown at 15 on both of its longitudinal edges, so that the blade may be 85 reversed, the blade being sharpened also upon its end, if desired, as clearly shown in Fig. 1 of the drawings. The angle members 9 which go to make up the table are connected at their ends by means of a bolt 90 16 or the like, passing through the vertical flanges 10 of the angle members.

In practical operation, the standard comprising the strips 7, assumes the inclined position shown in Fig. 1, and projects beyond 95 one end of the base 1, the strips 7 abutting against the shoulders 6, to prevent a downward swinging movement of the strips 7. However, it is possible by tightening

up the bolt 8 to hold the strips 7 in a position approaching the vertical more closely than indicated in Fig. 1. The table embodying the angle members 9 may be tilted 100 on the bolt 12 until the table assumes the desired angle with respect to the horizontal, whereupon the bolt 12 may be tightened up.

The bolt 16 serves to prevent relative movement between the angle members 9 and maintains the horizontal flanges 11 of the angle members in a common plane. The 110 blade 14 may be tilted to assume any desired angle, the blade swinging on the bolt

12. However, after the bolt 12 has been tightened up, the blade 14 will remain in its adjusted position, being bound between the depending, vertical flanges 10 of the angle members 9.

In practical operation, the operator sits astride of the base 1 and slides the potato which is to be cut along the table defined by the horizontal flanges 11 of the angle members 9, the potato coming into contact with the blade 14 and being severed thereby. After the potato has been cut to a sufficient extent the parts of the potato may be permitted to drop downwardly off the table, 15 into a suitable receptacle (not shown), it being observed that, owing to the fact that the standard composed of the strips 7 projects beyond one end of the base 1, the operation above described may be carried out 20 readily.

Having thus described the invention, what is claimed is:—

1. In a device of the class described, a base having a smooth upper surface adapted to 25 serve as a seat for an operator straddling the base; an inclined standard secured at its inner end to the base and projecting outwardly beyond one end of the base, the space below the outwardly projecting end of the standard being open and unencumbered; a table mounted on the outer end of the standard and having a flat and unencumbered upper face; and a blade projecting upwardly from the table.

2. In a device of the class described, a supporting structure; an inclined standard projecting from the supporting structure; a table carried by the upper end of the standard; a blade mounted to swing in a substan-

tially vertical plane with respect to the table, 40 for adjustment; and means for holding the blade rigidly in adjusted positions with respect to the table.

3. In a device of the class described, a supporting structure; a relatively fixed 45 standard projecting from the supporting structure; a table mounted to tilt on the upper end of the standard; a movable blade upstanding from the table; and means for holding both the blade and the table fixed 50 with respect to the standard.

4. In a device of the class described, a standard; a table mounted to tilt on the upper end of the standard; a blade mounted to swing in a substantially vertical plane 55 with respect to the table; and a common means coacting with the blade, the table and the standard, to hold the table in adjusted positions with respect to the standard and to hold the blade in adjusted positions with 60 respect to the table.

5. In a device of the class described, a table composed of a pair of angle members embodying vertical and horizontal flanges; a connection uniting the vertical flanges of 65 the angle members; a blade having its lower end engaged between the vertical flanges of the angle members; a standard; and a combined clamping and pivot device uniting the upper end of the standard, the vertical 70 flanges of the angle members and the blade.

In testimony that I claim the foregoing as my own, I have hereto affixed my signature in the presence of a witness.

SAMUEL F. RICHARDSON.

Witness:

LE ROY SHERMAN.
